UNITED STATES PATENT OFFICE.

JEAN LUCIEN ABADIE, OF SANTA BARBARA, CALIFORNIA.

PORTABLE SERVING-BUFFET.

1,240,163.

Specification of Letters Patent. Patented Sept. 18, 1917.

Application filed August 12, 1916. Serial No. 114,493.

To all whom it may concern:

Be it known that I, JEAN LUCIEN ABADIE, a citizen of the French Republic, residing at Number 624 State street, Santa Barbara, 5 State of California, United States of America, have invented certain new and useful Improvements in Portable Serving-Buffets; and I do hereby declare that the following is a full, clear, and exact description of the invention, such as will enable others skilled in the art to which it appertains to make and use the same.

The present invention relates to portable serving tables and more particularly to a 15 buffet table to be used in lunch rooms and the like, as described in my copending application Serial Number 94,370, filed May 3, 1916.

An object of the present invention is to 20 provide a portable table of the character aforesaid whereby foods, liquids and other articles used in a lunch room may be carried and the compartments for retaining the articles may be all arranged within the table 25 thereby giving a good appearance to the table and the foods within the table may be arranged and so exposed to view as to appear appetizing to the patrons of the lunch room.

With the above and other objects in view 30 which will hereinafter appear as the description continues, the invention consists of the novel features of construction and the formation of parts as will be hereinafter 35 more fully described and particularly pointed out in the appended claim.

In the accompanying drawings is shown 40 the simple and preferred form of the invention it being, however, understood that no limitation is necessarily made to the precise structural details herein exhibited but the right is hereby reserved to any changes or alterations that may be had and which come within the scope of the invention with- 45 out departing from the spirit thereof or sacrificing the efficiency of the same.

In the accompanying drawings:

Figure 1 is a side elevation of the table embodying the present invention;

50 Fig. 2 is a similar view having a portion of the drawers thereof broken away;

Fig. 3 is a vertical longitudinal section;

Fig. 4 is a vertical transverse section taken on the line 4-4 of Fig. 2;

55 Fig. 5 is a vertical transverse section taken on the line 5-5 of Fig. 2;

Fig. 6 is a horizontal sectional view taken on the line 6-6 of Fig. 2;

Fig. 7 is an end elevation;

60

Fig. 8 is a rear end elevation;

Fig. 9 is a plan view;

Fig. 10 is a plan view with the extendible tables open;

Fig. 11 is a plan view of one of the extendible tables removed;

65

Fig. 12 is a side elevation of the same; and,

Fig. 13 is a detail perspective view of the metallic storing chamber adapted to be arranged within the table.

70

Referring to the accompanying drawings wherein the like and corresponding parts are designated by similar reference characters throughout the several views—

The table forming the subject matter of 75 the present invention comprises a base portion 1 supported upon the casters 2 and supported upon the base portion 1 are the vertical end standards 3 and also the intermediate standards 4. Arranged upon 80 the intermediate standards 4 is a supplemental frame comprising a base portion 5, end partition walls 6 and intermediate partition walls 7 which divide the supplemental frame into three sections. Arranged 85 within the intermediate section are the shelves 8 and 9 whereas one of the end sections has arranged therein a shelf 10 and the other end section has arranged therein a shelf 11 forming a continuation of the shelves 8 90 and 10 and also a plurality of shelves 12. The upper end of the intermediate section is closed by means of the top 13 whereas the outer ends of the upper sections are open so that access may be gained to the interior of the 95 two outer sections. A top 14 for the table is provided comprising a stationary intermediate section 15 and the extendible table sections 16. The extendible table sections have each extended therefrom a pair of 100 bars or arms 17 adapted to slide within the guideways 18 whereby the extendible top may be closed as better shown in Fig. 9 or opened as shown in Fig. 10. Arranged upon the rear support 4 are a plurality of 105 shelves 19 upon which various articles may be arranged and these shelves are housed within the table. When it is desired a suitable cover or folded door (the latter not being shown) may be carried by the table for 110 completely housing the shelves 19 and the contents supported thereby. The forward

wall 4 divided into a plurality of shelves 20 which are also housed within the table and this forward end of the table may be also completely housed by providing a curtain or boltable door (the latter not being shown) which may extend over the entire front end of the table.

Adapted to rest upon the shelf 11 is a metallic casing 21 having substantially a **U** shaped configuration in cross section and provided with two compartments 22 and 23. Leading from the lower end of each of the compartments 22 and 23 are openings in which are adapted to be placed the intake ends of the faucets 24. Adapted to be arranged within the **U** casing 21 is a metallic casing 25 having leading therefrom the faucet 26 and the upper ends of the casings 21 and 25 are adapted to be closed by means of 20 a cover 27.

The lower portion 1 of the table has a partition 28 arranged therein dividing the same into two sections and the opposite sides of the sections are at all times open and also 25 articles of food or culinary articles such as dishes to be used in the lunch room may be placed in these compartments upon the bottom 1 of the table. The shelves 8, 10 and 12 arranged within the supplemental portion of 30 the table are also adapted to receive articles of food or culinary articles but the opposite side walls of the supplemental casing are adapted to be closed by means of the slide- 35 able doors. The slideable doors arranged at each side of the supplemental frame comprise the end sections 29 which are adapted to close the end sections of the supplemental frame and a pair of sliding intermediate doors 30 are provided for closing the medial 40 section of the supplemental frame. Arranged upon the shelf 9 of the intermediate section is a sliding tray 31 for holding knives, forks and spoons, or other silver- 45 ware adapted to be used by the patrons of the lunch room. The shelves 19 and 20 arranged at the opposite ends of the table provide supports for additional articles of food such as cakes and pies and which articles will be in the immediate view of the patrons.

50 The compartments 22 and 23 may contain milk and cream or similar liquids, whereas the compartment 25 may contain ice water or a similar cooling agent and the cold air thrown off by this cooling agent contained

within the compartment 25 may travel 55 through the perforations 32 arranged within the partitions of the table so that this cold air may travel through the various compartments of the table for cooling the foods carried thereby.

60 By providing the top of the table with the movable section 16 access may be gained to the upper end of the end sections of the supplemental frame and also these extendible sections 16 may be used when so ex- 65 tended for supporting various dishes which are to be served to the patrons of the lunch room.

From the foregoing it is obvious that I have provided a portable buffet serving table 70 in which may be arranged various foods and culinary articles to be used by the patrons of the lunch room, that the table may be easily transported around a lunch room and the various articles of food contained 75 therein may be shown to the immediate view of the patrons, thereby making a complete disclosure of the foods as sold by the lunch room and setting forth numerous foods from which the patrons may select 80 foods desired in a more appetizing manner.

Having thus fully described my invention, what I claim as new and desire to secure by Letters Patent is:

A portable buffet serving table comprising- 85 a base portion consisting of a bottom, end and intermediate standards supported thereupon, a supplemental frame arranged between said intermediate standards, a partition for dividing said supplemental frame 90 into sections, shelves arranged within said base portion and supplemental frame, slideable doors for closing the opposite sides of said supplemental frame, a top carried by said base portion, said top adapted to cover 95 said base portion and said supplemental frame, extendible sections arranged within said top and means whereby when said ex- 100 tendible sections are opened access may be gained into the supplemental frame for the purpose set forth.

In witness whereof I have hereunto set my hand:

JEAN LUCIEN ABADIE.

Witnesses:

E. M. EDWARDS,
LOUIS G. DREYFUSS.
